STOKER ATTACHMENT

Application filed April 6, 1929. Serial No. 353,139.

This invention relates to stokers for furnaces in which fuel is fed automatically from a hopper to the furnace chamber by a conveyer. In the operation of such stokers, with some kinds of fuel, the fuel is apt to stick in the hopper and to arch over the conveyer, and when this occurs the feed of fuel from the hopper to the furnace is irregular, or it may stop altogether.

10 The purpose of the present invention is to provide simple and effective means for preventing the fuel from sticking and arching in the hopper. I have found that the adherence of the finer particles of fuel, particularly if moist, to the walls of the hopper, is a main cause of the clogging of the hopper, and I have therefore provided means operated by the conveyer for vibrating the hopper walls in order to loosen the fuel which is on and adjacent the walls. The means preferably employed for vibrating the hopper walls comprises one or more resilient rods secured at their upper ends to the walls of the hopper at opposite sides of the axis of the conveyer and extending downwardly through the hopper into position to be moved and tripped by the conveyer, to jar the hopper walls. As these rods extend through the body of fuel in the hopper, it will be evident 20 that they will also agitate the mass of fuel so that if the fuel has any tendency to arch over the conveyer, this agitation will prevent arching.

In the accompanying drawing,

35 Fig. 1 is a section through part of a furnace to which is applied a mechanical stoker having my improvements therein, the stoker being shown in side elevation partly broken away;

40 Fig. 2 is a central vertical section through the fuel hopper and conveyer, taken longitudinally of the latter; and,

Fig. 3 is a section through the fuel hopper on the line 3—3 of Fig. 1.

45 Referring to the drawing, *a* indicates the combustion chamber of a furnace, and *b* indicates a mechanical stoker comprising a fuel hopper 1, a pipe 2, leading from the lower part of the hopper to a firepot 3, and a screw conveyer 4 in the pipe for carrying the fuel

from the hopper to the firepot. The screw conveyer is rotated very slowly by an electric motor (not shown), and reducing gearing contained in a casing 5. Air is supplied to the furnace through a conduit 6 from a 55 blower 7.

In the operation of the stoker, a supply of fuel, such as soft coal, is placed in the hopper and the conveyer feeds this fuel to the furnace as fast as it is required, the speed of the motor which drives the conveyer being regulated by temperature-controlling devices, in well known manner. As the fuel is carried from the bottom of the hopper, if the coal sticks in the hopper and arches over 65 the conveyer screw, the supply of coal to the furnace will be irregular or may stop altogether.

I have found that the adherence of the fuel, particularly if moist, to the side walls 70 of the hopper is a main cause of the clogging of the hopper, and I have therefore provided simple means for vibrating the side walls of the hopper, to loosen the fuel therefrom, and by the same means the mass of 75 fuel in the hopper is agitated so that the tendency of the fuel to arch is avoided.

In carrying out the invention, I provide one or more resilient devices, secured to the upper portions of the side walls of the hopper,—that is, the walls which are at opposite sides of the axis of the conveyer, and extending downwardly in the hopper into position to be put under tension by the convolutions of

the conveyer, and then tripped, with the result that the side walls of the hopper, which are formed of sheet metal, are placed under strain while the resilient device is being moved by the conveyer to the tripping position, and when the strain is relieved these 85 walls vibrate and the fuel is loosened from their surfaces and arching of the fuel over the conveyer is prevented.

To add to this effect, these devices may be arranged so that when tripped they will strike the wall of the hopper. As these resilient devices extend downwardly through the hopper, they also agitate and break up the mass of fuel in the center of the hopper when moved and tripped

50

The resilient devices referred to may take various forms. In the drawing, I have shown two such devices 8 and 9, which are alike except that the device 8 is curved so that the 5 part contained between its ends normally lies against the rear wall 3^a of the hopper. The device 8, composed of a metal rod 8, is twisted at the center, as shown at 8^a, and the two halves 8^b of the rod diverge from the center. 10 The ends of these halves or arms 8^b are secured rigidly to the upper parts of the side walls 1^a and 2^a of the hopper, while the twisted central portion 8^a lies in the path of movement of the convolutions of the conveyer 4. 15 The arms 8^b may be connected by cross-pieces 8^c for strengthening the device, and also for assisting in breaking up the mass of fuel. The arms extend downwardly from their 20 points of attachment to the side walls and are bent, below the cross-pieces 8^c, so as to lie against the back wall of the hopper.

The resilient device 9 is substantially the same as the device 8, but it is shown straighter and its ends are connected to the side walls of 25 the hopper adjacent the front wall, and it does not lie against the wall as does the device 8.

In operation, the conveyer turns in the direction indicated by the arrow in Fig. 2, and 30 the convolutions of the conveyer, engaging the heads 8^a and 9^a of the rods 8 and 9, move these heads to the left and put the rods under tension and to some extent warp the side walls of the hopper. As the conveyer continues to 35 rotate, each head finally trips over the convolution which it engages and the rods spring backward, relieving the strain on the side walls of the hopper and causing them to vibrate. The rod 8 also strikes the latter wall 40 3^a, thus amplifying the vibrations. Of course, if the fuel is feeding properly from the hopper, so that the spaces between the convolutions of the screw are filled with fuel, the resilient devices will not spring back to 45 their normal positions with great force because their movements will be obstructed by the fuel; but if the downward movement of the fuel in the hopper becomes slightly sluggish, so that the fuel is not well packed 50 around the conveyer at the bottom of the hopper, the resilient devices will snap back vigorously, shaking the walls of the hopper and also loosening the mass of fuel between the walls, so that the tendency of the fuel to 55 clog and arch will be overcome.

What I claim is:

1. In a stoker, a fuel hopper having sheet metal walls, a fire pot, a pipe leading from the former to the latter, a screw conveyer in 60 the hopper and pipe and means for vibrating one of the hopper walls at one side of the axis of the conveyer comprising a resilient member secured to said wall and extending downwardly through the hopper into position to be moved and tripped by the convolu-

tions of the conveyer, said member, while being moved to the tripping position, adapted to put said wall under strain.

2. In a stoker, a fuel hopper having sheet metal walls, a fire pot, a pipe leading from the former to the latter, a screw conveyer in the hopper and pipe and means for vibrating one of the hopper walls at one side of the axis of the conveyer comprising a resilient member secured to said wall and extending 70 downwardly through the hopper into position to be moved and tripped by the convolutions of the conveyer, said member, while being moved to the tripping position, adapted to put said wall under strain and adapted, 75 when tripped, to strike the hopper.

3. In a stoker, a fuel hopper having sheet metal walls, a fire pot, a pipe leading from the former to the latter, a screw conveyer in the hopper and pipe and means for vibrating 80 the walls of the hopper located at opposite sides of the axis of the conveyer comprising a V-shaped rod secured at its ends to said walls and extending downwardly through the hopper into position to be moved and 85 tripped by the convolutions of the conveyer, said rod, while being moved to the tripping position, adapted to put said walls under strain.

4. The combination with a furnace, of a 95 stoker comprising a fuel hopper having sheet metal walls, means for conveying fuel from the bottom of the hopper to the furnace, and means for vibrating one of the hopper walls at one side of the conveying means comprising a resilient member secured to said wall and adapted to be moved and tripped by the conveying means, said member, while being moved to the tripping position, adapted to put said wall under strain. 100

In testimony whereof I affix my signature.
ROBERT H. S. HUGHES.
